STOCKING

Warren Goff, Philadelphia, Pa.

Application June 2, 1950, Serial No. 10,313

Term of patent 14 years

(Cl. D47—7)

To all whom it may concern:

Be it known that I, Warren Goff, a citizen of the United States, and a resident of Philadelphia, county of Philadelphia, State of Pennsylvania, have invented a new, original, and ornamental Design for a Stocking, of which the following is a specification, reference being had to the accompanying drawings, forming a part thereof, wherein:

Figure 1 is a fragmentary perspective view of the rear of the stocking showing my new design; and

My design is characterized by the parallel lines of spaced blocks formed of the lighter body yarn in the reinforced area of the heel and foot portion as shown.

I claim:

The ornamental design for a stocking, as shown and described.

WARREN GOFF.
